CLAIM

The ornamental design for container dome, as shown and described.

DESCRIPTION

FIG. 1 is an elevational view of a container dome embodying my new design, the broken line showing the container finish, sidewall and base being for illustrative purposes only and forming no part of the claimed design;

FIG. 2 is a perspective view of the container dome of FIG. 1;

FIG. 3 is a top plan view of the container dome of FIG. 2;

FIG. 4 is a bottom plan view of the container dome of FIG. 2; and,

FIG. 5 is an elevational view of the container dome of FIG. 2.
